UNITED STATES PATENT OFFICE.

JOSEPH M. HALL, OF HAMILTON, ONTARIO, CANADA, ASSIGNOR TO HALL DRAFT GEAR CORPORATION, OF BUFFALO, NEW YORK, A CORPORATION OF NEW YORK.

SHOCK ABSORBER.

Application filed April 17, 1922, Serial No. 554,229. Renewed October 24, 1924

To all whom it may concern:

Be it known that I, JOSEPH M. HALL, a citizen of the United States, residing in Hamilton, in the county of Wentworth and Province of Ontario, Dominion of Canada, have invented new and useful Improvements in Shock Absorbers, of which the following is a specification.

This invention relates to a shock absorber which is more particularly designed for use on railway cars and the like, although the same may also be used for other purposes in which a cushioning effect is required between two relatively movable parts, and more particularly to a shock absorber in which a plurality of sets of alternating or intercalated plates are employed which slide frictionally lengthwise relatively to each other and which are subjected to increasing lateral pressure during the buffing and pulling actions of the draft gear of the railway car and reduced lateral pressure during the relaxation of the draft gear.

It is the object of this invention to provide simple, compact and effective means for causing the friction plates to be pressed together laterally promptly and offer a greater frictional resisting effect to the load, and also to secure a more prompt and free release of the frictional contact between the several plates during relaxation of the draft gear and thereby obtain a better compression or closing up of the shock absorber and a more free and prompt release of the same.

In the accompanying drawings:

Figure 1 is a horizontal longitudinal section showing this improved shock absorber organized for use as a friction shock absorbing gear for railway cars, the parts being represented in the position which they occupy when the gear is released. Figure 2 is a similar view showing the gear under a load and compressed to its maximum extent. Figures 3, 4 and 5 are fragmentary longitudinal sections, taken on the correspondingly numbered lines in Figs. 1 and 2, respectively. Figures 6 and 7 are vertical cross sections, taken on the correspondingly numbered lines in Fig. 1. Figure 8 is a perspective view of one of the housings, cages or caps forming part of the shock absorbing gear. Figure 9 is a similar view of

one of the friction plates thereof. Figure 10 is a similar view of one of the wedge plates of the same. Figure 11 is a similar view of one of the spring seats of this gear. Figure 12 is a perspective view of one of the wedges or wedge blocks forming part of this gear. Figure 13 is a similar view of one of the releasing bars of the same.

Similar characters of reference refer to like parts throughout the several views.

10, 10 represent the longitudinal central sills of a car frame, 11 the front draft lugs or stops arranged on the front parts of the opposing sides of these sills, 12 the rear draft lugs or stops and 13 the transverse carrying bar or iron connecting the lower sides of these sills at a point between the front and rear draft lugs thereof and adapted to support the shock absorbing gear on its underside.

The shock absorbing gear containing my invention is arranged between the front and rear draft lugs and the adjacent part of the central sills of the car frame and is embraced by a yoke having upper and lower longitudinal bars 14 which are spaced apart, a rear cross head 15 connecting the rear ends of the side bars 14 and two coupling arms 16 projecting forwardly from the front ends of these side bars. The rear end of the shank 17 of the car coupler is arranged between the arms 16 of the yoke and connected therewith by means of a key 18, or any other suitable means.

The shock absorbing gear which embodies my improvements and co-operates with the above-mentioned parts of the draft gear of the car, in its preferred form is constructed as follows:

Arranged within the front and rear parts of the slot formed within the yoke are front and rear housings, cages or caps which have their open or concave sides facing each other, each of these housings being preferably rectangular in cross section, and the front housing being provided on its horizontally opposite sides with two flat longitudinal parallel friction walls 19, 19 and a front transverse follower 20 connecting the front ends of these walls, and the rear housing being provided on horizontally opposite sides with two longitudinal parallel flat friction walls 21 and a rear transverse follower

22 connecting the rear ends of the side walls 21, the walls and follower of each housing being preferably formed integrally, as shown in Figs. 1 and 2.

6 Within horizontally opposite sides of the space of these housings are arranged two sets of intercalated friction plates 23 which are adapted to frictionally engage each other with a longitudinally sliding movement 10 relatively to each other and thus serve as a means for absorbing or taking up part of the shock, work or load, during buffing and pulling strains when coupling or pushing the car or when pulling the same. The 15 plates of one set alternate with those of another set on the same side of the gear so that these plates overlap one another and engage their flat surfaces in a direction parallel and lengthwise of the direction of 20 movement of the coupler and associated parts, the front ends of the front sets of both pairs of friction plates are adapted to be engaged by the follower and transverse front wall of the front housing, and the 25 rear ends of the rear sets of both pairs of friction plates are adapted to be engaged by the rear follower or transverse wall of the rear housing. Each of these friction plates is provided in its opposite longitudinal 30 edges near the outer end of the respective plate with notches 24, thereby forming inwardly facing shoulders 25 on these plates adjacent to the outer end thereof, while the inner part of each of these plates is correspondingly reduced in width equal to the 35 distance between the notches 24, as shown at 26 in Figs. 3 and 9.

The inner side of the innermost friction plates of both pairs are engaged adjacent to the front follower 20 by means of two front wedge plates or shoes 27 and adjacent to the rear follower 22 by a pair of rear wedge plates or shoes 28. Each of these wedge plates is provided on its inner side with an 40 outwardly facing incline 29 and with an inwardly facing incline 30, the outwardly facing incline being arranged at a comparatively sharp or acute angle and the inner incline 30 being arranged at a comparatively 45 abrupt or obtuse angle, as best shown in Fig. 2.

50 31, 32 represent front and rear wedges or wedge blocks which are adapted to engage their outer sides with the inner sides of the front and rear followers 20, 22, respectively, and which are provided on their inner ends with the inwardly facing inclines 33 arranged at the same angle as the outer inclines 29 of the wedge plates and adapted to 55 engage the same. 34 is a comparatively light releasing spring preferably of helical form, arranged lengthwise in the center of the gear and engaging its opposite ends with the opposing sides of the front and rear 60 wedges 31, 32.

35, 38 represent front and rear spring seats or washers, the front spring seat being provided on its outer side adjacent to its margin with outwardly facing inclines 36 which engage with and are arranged at the 70 same angle as the inwardly facing inclines 30 of the front wedge plates 27, while the rear spring seat 38 is provided with similar outwardly facing inclines 36 which engage with the inwardly facing inclines 30 of the 75 rear wedge plates, as shown in Figs. 1 and 2.

37 represents a comparatively heavy friction spring, preferably of helical form, surrounding the releasing spring and bearing 80 at its opposite ends against the opposing inner sides of the spring seats 35, 38.

39, 39 and 40, 40 represent front and rear pairs of releasing bars, the members of the front pair being arranged transversely 85 on opposite sides of the front wedge and having their ends projecting in the notches 24 in the longitudinal edges of the front sets of friction plates and the members of the rear pair of releasing bars being arranged 90 on opposite sides of the rear wedge and having their ends projecting into the notches 24 in the longitudinal edges of the rear sets of friction plates.

On opposite sides each wedge is provided 95 with a pair of outwardly projecting shifting lugs or shoulders 42, 42, which are adapted to bear at times against the inner edge of the adjacent releasing bar. On its opposite longitudinal edges each of the wedge plates 100 or shoes is provided with outwardly facing inclines 41 each of which is adapted to engage with an inwardly facing incline 45 on the adjacent part of the inner edge of one of the releasing bars. 105

For convenience in holding the elements of the shock absorbing mechanism in their proper relative position during transportation and for convenience in mounting the same in a draft gear of a car or removing the same therefrom, the front and rear housings are temporarily connected by a tie bolt 43 which is adapted to extend through the releasing spring and through corresponding openings in the followers 20, 22, which tie bolt when in use has its head and nut seated in recesses 44 in the outer sides of the followers, as best shown in Fig. 4. 110

The operation of this shock absorbing mechanism is as follows: 120

When the shock absorber is fully released, relaxed or open, as shown in Figs. 1 and 5, the front and rear housings bear with their followers against the front and rear stops and against the front arms 16 and rear cross head 15 of the yoke, the front and rear wedges are spread farthest apart by the releasing spring, the spring seats are pushed outwardly to their extreme positions by the friction spring together with 125 130

the wedge plates which bear with their outwardly facing inclines against the inclines of the wedges, the releasing bars are moved into their outermost positions by the shifting lugs of the wedges and the co-operating inclines of the releasing bars and wedge plates, and the front and rear sets of friction plates of both pairs are pulled apart the maximum extent by engagement of the releasing bars with the shoulders 25 of the friction plates, which latter however at this time, are separated at their outer ends from the followers 20, 21, whereby relieving the lateral outward pressure against the wedge plates and the friction plates against each other due to the release spring forcing the wedge out of working contact with the wedge plates.

Upon now moving one of the housings toward the other, as for instance, the front housing toward the rear housing, to the position shown in Figs. 2 and 4, which would be the case during a maximum buffering action, the first effect would be an inward movement of the front housing and the front wedge independently of the front sets of friction plates, thereby causing both front and rear wedges, by engagement of their inclines with the outer inclines 29 of the wedge plates to press the same laterally outward, whereby the several sets of intercalated friction plates are caused to engage each other with increased friction contact. The lateral outward movement of the wedge plates at this time is facilitated by engagement of the inner inclines of the wedge plates with the outwardly facing inclines on the spring seats which reduces the frictional resistance between the wedge plates and the spring seats thereby insuring a quick and prompt gripping action of the friction plates upon each other.

During this initial inward movement of the front wedge both the front and rear wedge plates are moved lengthwise slightly and a slight increase occurs in the compression of the friction spring. After this initial inward movement of the front wedge and increased grip between the friction plates, the followers of the front and rear housings both engage with the outer ends of the front and rear sets of friction plates and cause the front sets of friction plates to move backwardly relatively to the rear sets of these plates, which movement is not only increasingly resisted by the friction and releasing springs, but also increasingly resisted by the frictional contact between the relatively stationary rear and the longitudinally movable front sets of friction plates by reason of the fact that the increasing resistance of the friction spring causes an increasing lateral wedge action of the wedges against the wedge plates and consequently an increasing frictional grip of the

friction plates upon each other and a proportionate increase in the cushioning effect upon the load from which the buffering shock originates. During this frictional sliding engagement of the front sets of friction plates with the rear sets of friction plates the latter will be moved slightly backward until their outer ends abut against the rear follower 22, thus carrying the shoulders 25 of the rear friction plates away from the rear releasing bar, as shown at the left of Fig. 2. The shoulders 25 of the front set of friction plates however remain in contact with the outer edge of the front releasing bars 39 and move the latter inwardly to the same extent. During this closing up or compression of the shock absorber the shifting lugs 42 of the wedge will move slightly away from the inner edge of the front releasing bars and the rear releasing bars 40 will be carried rearwardly slightly by reason of the slight rearward movement of the rear wedge plates and spring seat during which time the rear wedge plates push the rear releasing bars rearwardly and away from the shifting lugs 42 of the rear wedge, as shown at the left of Fig. 2.

Upon now removing the load which operated to compress the shock absorber the first effect is for the releasing spring to push the front wedge forwardly and reduce the wedge action of the same against the front pair of wedge plates, whereby the latter are permitted to move both forwardly and inwardly and the friction spring to expand proportionately so as to reduce its resisting effect and the outward pressure of the wedge plates on the friction plates, whereby the frictional contact between the latter is released quickly and fully and the shock absorber is permitted to expand or open promptly and effectively.

It is possible to release the wedges from the wedge plates to accomplish the above-mentioned result due to the angle of contact between the wedges and the wedge plates being more acute or sharp than the angle of contact between the wedge plates and the spring seats inasmuch as the force of the friction spring moves the wedge plates against the angular face on the release bars. This angle is inclined away from the friction plates thereby producing a tendency to force the wedge plates away from the friction plates and reducing the frictional grip of the latter on each other.

As the front wedge and wedge plates move forwardly during release of the shock absorber, the shifting lugs 42 of the front wedge engage with the inner edge of the front releasing bars and push the latter into their foremost position. During this forward movement of the front releasing bars the same engage with the shoulders 25 of the front sets of friction plates and carry

the latter to their foremost position. During the outward movement of the front wedge plates their inclines 41 engage with the inclines 45 of the front releasing bars 5 and thereby not only assist in pushing the front sets of friction plates forwardly, but the action of these co-operating inclines also causes the front wedge plates to be drawn laterally inward and thus relieve the lateral 10 outward pressure of the same against the friction plates, whereby the frictional contact between these plates is reduced and the shock absorber is permitted to open or release more promptly. When the shock absorber is fully expanded and the front follower 20 has been moved away from the outer ends of the front sets of friction plates and the rear sets of friction plates have also been carried forwardly by frictional contact 15 with the front friction plates until the outer ends of the rear friction plates have been moved away from the rear follower 22 and the shoulders 25 of the rear friction plates are again in engagement with the outer edge 20 of the rear releasing bars 40.

When the shock absorber is subjected to a pulling load the action is reversed, that is to say, the front follower and wedge are stationary while the rear follower, wedge, 30 wedge plates and parts associated therewith move and function in the same manner as that previously described with reference to the front wedge, wedge plates, spring seat and releasing bar during a buffing and releasing operation.

It will be noted that in this construction the pressure of the friction spring is transmitted indirectly through the wedge plates to the releasing bars and also indirectly 40 from the releasing spring through the wedges to the releasing bars for restoring the shock absorber to its open or released position.

The angular or wedging engagement between the wedge plates or shoes and the spring seats is intended primarily to cause the wedge plates to move laterally outward freely and press the friction plates quickly together and against the side walls of the 50 housings. When, however, releasing the shock absorber this wedging engagement between the wedge plates and spring seats operates negatively and would retard a prompt release of the pressure of the wedge plates against the friction plates. This tendency to hold the wedge plates against the friction plates is however offset by the force of the wedging engagement of the wedge plates against the releasing bars so that 55 when the wedge plates are moved outwardly by the friction spring, these plates will be withdrawn laterally inward from the innermost friction plates and thus counteract or negative the lateral outward pressure produced by the wedging engagement between 60

the wedge plates and spring seats and thereby cause the shock absorber to release freely, promptly and effectively.

The advantage in this shock absorber is that the wedge plates or shoes slide laterally 70 outward more easily and furnish a better compression when applying the shock absorber and also a more prompt and free release when relaxing the load on the same, and the same also provides a much greater 75 shock absorbing capacity within the limits of space now available and it accomplishes this purpose by means which act promptly both during closing, compression or application and during opening, releasing or relaxation, 80 which will stand the severest usage and not give way under the hardest shocks, and which can be produced economically and are not liable to get out of order.

I claim as my invention:

1. A shock absorber comprising a plurality of sets of friction plates which are intercalated and adapted to slide lengthwise relatively to one another, a housing having a side wall engaging with the outermost of said friction plates and a follower which is adapted to engage with the outer ends of the friction plates of one set, a wedge plate engaging with the innermost of said friction plates, and provided with an outwardly facing incline, a wedge having an inwardly facing incline which engages said outwardly facing incline of the wedge plate, a releasing bar adapted to be moved inwardly by said friction plates which are engaged 95 by said follower and having a wedging engagement with said wedge plate, a releasing spring engaging with said wedge, and a friction spring operating on said wedge plate.

2. A shock absorber comprising a plurality of sets of friction plates which are intercalated and adapted to slide lengthwise relatively to one another, a housing having a side wall engaging with the outermost of 110 said friction plates and a follower which is adapted to engage with the outer ends of the friction plates of one set, a wedge plate engaging with the innermost of said friction plates and provided with an outwardly 115 facing incline, a wedge having an inwardly facing incline which engages said outwardly facing incline of the wedge plate, a releasing bar adapted to be moved inwardly by said friction plates which are engaged 120 by said follower and having a wedging engagement with said wedge plate, a releasing spring engaging with said wedge, a spring seat engaging said wedge plate, and a friction spring engaging said spring seat.

3. A shock absorber comprising a plurality of sets of friction plates which are intercalated and adapted to slide lengthwise relatively to one another, a housing having a side wall engaging with the outermost of 130

said friction plates and a follower which is adapted to engage with the outer ends of the friction plates of one set, a wedge plate engaging with the innermost of said friction plates and provided with an outwardly facing incline, a releasing bar adapted to be moved inwardly by said friction plates which are adapted to be engaged by said follower, a wedge plate engaging with the innermost of said friction plates and having a wedging engagement with said releasing bar, a wedge having a wedging engagement with said wedge plate and provided with an outwardly facing shoulder adapted to engage said releasing bar, a releasing spring engaging said wedge, and a friction spring operating on said wedge plate.

4. A shock absorber comprising a plurality of sets of friction plates which are intercalated and adapted to slide lengthwise relatively to one another, a housing having a side wall engaging with the outermost of said friction plates and a follower which is adapted to engage with the outer ends of the friction plates of one set, a wedge plate engaging with the innermost of said friction plates and provided with an outwardly facing incline, a releasing bar adapted to be moved inwardly by said friction plates which are adapted to be engaged by said follower, a wedge plate engaging with the innermost of said friction plates and having a wedging engagement with said releasing bar, a wedge having a wedging engagement with said wedge plate and provided with an outwardly facing shoulder adapted to engage said releasing bar, a spring seat having a wedging engagement with said wedge plate, a releasing spring engaging with said wedge, and a friction spring engaging with said spring seat.

5. A shock absorber comprising a plurality of sets of friction plates which are intercalated and adapted to slide lengthwise one upon another, a housing having a side wall engaging with the outermost of said friction plates and a follower adapted to engage the outer ends of one of said sets of friction plates and to be moved inwardly longitudinally thereby, said last-mentioned set of plates which are actuated by said follower being provided with inwardly facing shoulders, a releasing bar having an outer edge adapted to be engaged by said shoulders of the last-mentioned set of friction plates and provided with an inwardly facing incline, a wedge plate engaging the innermost of said friction plates and having two outwardly facing inclines, one of which engages with said inwardly facing incline of the releasing bar and also provided with an inwardly facing incline, a spring seat having an outwardly facing incline which engages the inwardly facing incline of the wedge plate, a wedge having an inwardly facing incline which engages the other one of the outwardly facing inclines of said wedge plate, and also provided with an outwardly facing shoulder adapted to engage said releasing bar, a releasing spring engaging

facing incline which engages the other one of the outwardly facing inclines of said wedge plate, a releasing spring engaging with said wedge, and a friction spring engaging with said spring seat.

6. A shock absorber comprising a plurality of sets of friction plates which are intercalated and adapted to slide lengthwise one upon another, a housing having a side wall engaging with the outermost of said friction plates and a follower adapted to engage the outer ends of one of said sets of friction plates and to be moved inwardly longitudinally thereby, said last-mentioned set of plates which are actuated by said follower being provided with inwardly facing shoulders, a releasing bar having an outer edge adapted to be engaged by said shoulders of the last-mentioned set of friction plates and provided with an inwardly facing incline, a wedge plate engaging the innermost of said friction plates and having two outwardly facing inclines one of which engages said inwardly facing incline of the releasing bar and also provided with an inwardly facing incline, a spring seat having an outwardly facing incline which engages the inwardly facing incline of the wedge plate, a wedge having an inwardly facing incline which engages the other one of the outwardly facing inclines of said wedge plate, and also provided with an outwardly facing shoulder adapted to engage said releasing bar, a releasing spring engaging with said wedge, and a friction spring engaging with said spring seat.

7. A shock absorber comprising a plurality of sets of friction plates which are intercalated and adapted to slide lengthwise one upon another, a housing having a side wall engaging with the outermost of said friction plates and a follower adapted to engage the outer ends of one of said sets of friction plates and to be moved inwardly longitudinally thereby, said last-mentioned set of plates which are actuated by said follower being provided with inwardly facing shoulders, a releasing bar having an outer edge adapted to be engaged by said shoulders of the last-mentioned set of friction plates and provided with an inwardly facing incline, a wedge plate engaging the innermost of said friction plates and having two outwardly facing inclines one of which engages said inwardly facing incline of the releasing bar and also provided with an inwardly facing incline, a spring seat having an outwardly facing incline which engages the inwardly facing incline of the wedge plate, a wedge having an inwardly facing incline which engages the other one of the outwardly facing inclines of said wedge plate, and also provided with an outwardly facing shoulder adapted to engage said releasing bar, a releasing spring engaging

- with said wedge, and a friction spring engaging with said spring seat, the co-operating inclines of the wedge and the wedge plate being arranged at an acute or sharp 5 angle and the co-operating inclines of the wedge plate and the spring plate being arranged at an obtuse or abrupt angle.
8. A shock absorber comprising a plurality of sets of friction plates which are intercalated and adapted to slide lengthwise one upon another, a housing having a side wall engaging with the outermost of said friction plates and a follower adapted to engage the outer ends of one of said sets of 10 friction plates and to be moved inward longitudinally thereby, said last-mentioned set of plates which are actuated by said follower being provided with inwardly facing shoulders, a releasing bar having an outer 15 edge adapted to be engaged by said shoulders of the last-mentioned set of friction plates and provided with an inwardly facing incline, a wedge plate engaging the innermost of said friction plates and having two outwardly facing inclines one of which 20 engages said inwardly facing incline of the releasing bar and also provided with an inwardly facing incline, a spring seat having an outwardly facing incline which engages the inwardly facing incline of the wedge plate, a wedge having an inwardly facing incline which engages the other one of the outwardly facing inclines of said wedge plate, and also provided with an outwardly 25 facing shoulder adapted to engage said releasing bar, a releasing spring engaging with said wedge, and a friction spring engaging with said spring seat, the co-operating inclines of the wedge and the wedge plate being at an acute angle and operating to press the wedge plate laterally outward upon moving the wedge longitudinally inward, and the co-operating inclines of the wedge plate and spring seat operating to move the wedge plate laterally outward upon moving the wedge plate longitudinally inward, and the co-operating inclines of the wedge plate and spring seat operating to move the wedge plate laterally outward upon moving the wedge plate longitudinally inward.
9. A shock absorber comprising a plurality of sets of friction plates which are intercalated and adapted to slide lengthwise one upon another, a housing having a side wall engaging with the outermost of said friction plates and a follower adapted to engage the outer ends of one of said sets of friction plates, and to be moved inward longitudinally thereby, said last-mentioned set of plates which are actuated by said follower being provided with inwardly facing shoulders, a releasing bar having an outer 30 edge adapted to be engaged by said shoulders of the last-mentioned set of friction

plates and provided with an inwardly facing incline, a wedge plate engaging the innermost of said friction plates and having two outwardly facing inclines one of which 35 engages said inwardly facing incline of the releasing bar and also provided with an inwardly facing incline, a spring seat having an outwardly facing incline which engages the inwardly facing incline of the wedge plate, a wedge having an inwardly facing incline which engages the other one of the outwardly facing inclines of said wedge plate, and also provided with an outwardly 40 facing shoulder adapted to engage said releasing bar, a releasing spring engaging with said wedge, and a friction spring engaging with said spring seat, the co-operating inclines of the wedge and the wedge plate being at an acute angle and operating to press the wedge plate laterally outward upon moving the wedge longitudinally inward, and the co-operating inclines of the wedge plate and spring seat operating to move the wedge plate laterally outward upon moving the wedge plate longitudinally inward, and the co-operating inclines of the wedge plate and spring seat operating to move the wedge plate laterally outward upon moving the wedge plate longitudinally inward, and the co-operating inclines of the wedge plate and spring seat operating to move the wedge plate laterally outward upon moving the wedge plate longitudinally inward.

10. In a friction shock absorbing mechanism, the combination with a longitudinally movable container, a follower, a plurality of relatively stationary plates within said container, a plurality of longitudinally relatively movable friction plates intercalated with said relatively stationary friction plates and adapted to be moved forward by said follower, pressure-transmitting and lateral pressure-creating means cooperable with said intercalated plates, a spring resistance associated with said pressure-transmitting and lateral pressure-creating means, and a releasing bar associated with said pressure-transmitting and lateral pressure-creating means and said longitudinal relatively movable friction plates and adapted when moved longitudinally backward to engage the longitudinally movable plates and to be moved forward idly by engagement therewith of said longitudinally movable friction plates when the latter are actuated by said follower, said releasing bar and said pressure-transmitting and lateral pressure-creating means being provided with co-operating wedging surfaces for reducing the pressure of said lateral pressure-creating means on said intercalated friction plates during the backward movement of said container and follower.

JOSEPH M. HALL.
